UNITED STATES PATENT OFFICE.

THOMAS ANDREWS, OF ROCKAWAY, NEW JERSEY, ASSIGNOR TO THE THOMAS ANDREWS MANUFACTURING COMPANY, OF ROCKAWAY, NEW JERSEY, A CORPORATION OF NEW JERSEY.

TUBE-CLEANER.

1,068,292.

Specification of Letters Patent. Patented July 22, 1913.

Application filed July 8, 1908. Serial No. 442,481.

To all whom it may concern:

Be it known that I, THOMAS ANDREWS, a citizen of the United States, residing at Rockaway, in the county of Morris and State 5 of New Jersey, have invented certain new and useful Improvements in Tube-Cleaners, of which the following is a specification.

The invention relates to improvements in tube cleaners and has particular reference to 10 an apparatus for cleaning scale and other corroding elements from the interior walls of boiler tubes and the like.

The apparatus is constructed to receive a motive agent preferably in the form of high 15 or low pressure air or steam but may have utilized in connection with the operative parts thereof a motive agent in the form of water and other fluids.

In the following is described in connection 20 with the accompanying drawings one embodiment of the invention, the features thereof being more particularly pointed out hereinafter in the claim.

In the drawings Figure 1 is a longitudinal 25 sectional view of the apparatus, parts being shown in elevation to more clearly illustrate the invention; and Fig. 2 is a cross sectional view on the line A—B of Fig. 1.

Similar numerals of reference indicate 30 similar parts throughout the several views.

In the drawings 1 designates the body of the casing having formed therein an eccentric bore indicated at 2 forming at that point a fluid chamber 3. Said casing 1 has formed 35 on one end thereof a threaded nipple 4 adapted to receive a head 5, said head 5 having formed thereon a threaded nipple 6 adapted to receive a coupling-head or pipe 7 which in turn communicates with any suitable source of fluid supply. The other end 40 of said casing 1 has formed thereon an extended reduced portion 8 adapted to receive one end of a hollow shaft 9, which has a bearing in the ends of the casing 1. 45 The said shaft 9 has slidably mounted therein a rod 12. The inner end of said rod 12 passes through the head 5 and has rigidly mounted thereon a shut-off disk 13 held adjustably in place on said rod 12 by means of 50 the lock-nut 14.

The shaft 9 has mounted thereon a rotary driving-head 15 extending the full length of said fluid-receiving chamber 3. Said rotary driving-head 15 has mounted

therein valves 16 mounted in recesses 17 55 formed in said rotary head. One end of said valves 16 is provided with enlarged portions 18 which taper toward the other end so that the outer surfaces 19 of said valves conform to the outer periphery of 60 the rotary driving head providing at that point a surface that will readily contact with the interior surface of chamber 3. The inner surfaces 20 of said valves 16 are formed in such a manner so that when said valves 16 65 are seated there will be a small fluid-receiving slot 21 formed between the smaller end of said valve in the head forming a passageway for the motive fluid. The fluid-receiving head 5 has formed therein a port or 70 passageway 22 adapted to convey the motive agent from the pipe connection through port 23 to by-ports 24 which in turn communicate with fluid-receiving slot 21 formed between said rotary head 15 and valves 16. 75 The casing 1 has also formed at its outer end a recess 25 having mounted therein a plunger-head 26 held normally closed by means of a spring 27. Said recess 25 communicates with shaft 9 at 28, providing at 80 that point means for supplying the operative parts of the apparatus with a lubricant. The fluid-receiving port 22, described above as being formed in fluid-receiving head 5, is 85 formed in said fluid-receiving head 5 in such a manner so that the outer opening thereof at 29 is adapted to be covered or closed by the shut-off disk 13.

The rod 12 has mounted thereon at its outer end a plunger 31 suitably mounted 90 in a chamber 32 formed in the body portion of rotary supporting-head 33 and connected or integral with shaft 15. Said rotary supporting-head 33 has pivotally mounted therein, as at 34, arms 35 provided at their 95 outer ends with means for receiving pins or studs 36 carrying a plurality of cutters 37. The pins or studs 36 have formed on their outer ends tapering heads 38 and at their inner ends or the end engaging said 100 arms 35 a lock-nut 39 adapted to assist in holding said cutters 37 in place on said pins or studs 36. Plunger 31 has mounted thereon a head 40 having pivotally mounted therein, as at 41, links 42 which are in turn 105 pivotally connected as at 43, to lugs 44 cast with or formed on said arms 35. Said shaft 9 has formed therein a fluid passage-

way 45 adapted to convey the motive agent from the source of supply to chamber 32, in said rotary supporting-head 33.

The casing 1 has formed therein an exhaust port 46 communicating with expansion chamber 3 at the lower edge of said expansion chamber, as at 47, which conveys the exhaust fluid to exhaust port 48, which in turn conveys said exhaust air to atmosphere through the outer end of said casing 1, as at 49. In order to assist the exhausting of expansion chamber 3, an auxiliary exhaust port 50 is provided communicating with expansion chamber 3 by means of by-ports 51. The exhaust air as conveyed through said port 50 is also carried to the atmosphere through the outer end of said casing 1. The rotary action of the apparatus cannot be started until the cleaner 20 arms are swung inwardly sufficient to move the rod 12 and disk 13 and thereby to open the port 22.

The operation of the apparatus is as follows. A fluid under pressure is received from any suitable source of supply (said source of supply is not shown in connection with the accompanying drawings) by fluid-receiving head 5, whence said fluid is conveyed through port 22 to feed port 23 through by-ports 24 to receiving-groove 21 formed between said rotary core 15 and valve 16. Said live fluid as received by said rotary head will instantaneously cause the rotary driving-head to rotate, which gradually increases in speed by means of the expansion of said live fluid in said expansion chamber 3. Immediately upon the rotation of said rotary driving-head the shaft 9 will be driven which in turn causes the driving-head 33 to rotate at the same rate of speed and the cutters 37, carried by arms 35 and lugs 36, to engage the interior walls of a tube and remove the scale or corroding element therefrom. The exhaust fluid will assist in removing the scale, etc., from the in-

terior of a tube after it has been displaced by said cutters. In case the interior diameter of a tube should by chance be larger than the main body of the tube, or the velocity of the driving-head too great, the fluid, as conveyed from the source of supply through air passageway 45 to chamber 32, will cause the arms 35 carrying the cutting-heads, to swing outwardly and draw rod 12 longitudinally of the apparatus and cause shut-off disk 13 to cover the mouth 29 of the live fluid port 22 and automatically stop the rotation of the motor. The automatic shut-off described as being associated with said rotating mechanism provides specific means of preventing any possible rupture to the tube, also any possible dislocation of the operative parts of the apparatus.

What I claim and desire to secure by Letters Patent of the United States is:—

A device of the character described comprising a hollow casing having a port in one end communicating with the interior thereof, a driving head in said casing having a valve adapted to either open or close said port within said casing, a hollow shaft having bearings within said driving head and provided at its front end with a head having a chamber therein, a plunger in said chamber having a rod connected therewith and extending through said hollow shaft, arms pivotally connected to said hollow shaft head, links pivotally connected to said arms and plunger, a coupling connected to said casing and forming a chamber at one end thereof, and a disk connected with said rod adapted to close the port of said casing within said last mentioned chamber.

In testimony whereof I have hereunto signed my name in the presence of two subscribing witnesses.

THOMAS ANDREWS.
